DESIGN FOR A TELEVISION VIEWING
FRAMEWilliam S. Leffler and Warren B. Green, Darien,
Conn.; said Green assignor to said Leffler

Application March 19, 1948, Serial No. 145,234

Term of patent 14 years

(Cl. D26—14)

To all whom it may concern:

Be it known that we, William S. Leffler and Warren B. Green, citizens of the United States, residing at Darien, in the county of Fairfield and State of Connecticut, have invented a new, original, and ornamental Design for a Television Viewing Frame, of which the following is a specification, reference being had to the accompanying drawing, forming a part thereof.

Figure 1 is a front elevation of a television viewing frame embodying our new design.

Figure 2 is a perspective view thereof.

Figure 3 is a side perspective view thereof showing the television viewing frame associated with a receiver cabinet shown in dotted lines and for illustrative purposes only.

We claim:

The ornamental design for a television viewing frame, substantially as shown and described.

WILLIAM S. LEFFLER.
WARREN B. GREEN.
